LOUD ACOUSTIC CONDENSER

Filed July 19, 1929

13 14 Inventor:
Philip E. Edelman,
By Banning & Banning
Attn. J. S. J.

UNITED STATES PATENT OFFICE

PHILIP E. EDELMAN, OF CHICAGO, ILLINOIS, ASSIGNOR TO EPHRAIM BANNING, OF CHICAGO, ILLINOIS

LOUD ACOUSTIC CONDENSER

Application filed July 19, 1929. Serial No. 379,359.

In acoustic condensers of the type shown and described in my pending application, Serial No. 352,201, there is a tendency of the flexible sheets forming the electrodes of the 5 condenser to produce a rustling sound when the loud speaker is going full blast.

An object of this invention is to provide a means whereby this rustling sound will be decreased, if not eliminated.

10 Another object is to improve the volume and quality of the sound produced by acoustic condensers.

This and other objects, as will hereinafter appear, are accomplished by this invention 15 which is fully described in the following specification, and shown in the accompanying drawings, in which—

Figure 1 is a transverse sectional view through an acoustic condenser embodying 20 the invention;

Fig. 2 is a partial slightly enlarged view of the same;

Fig. 3 is a view similar to Fig. 2 showing a modified form of the invention; and

25 Fig. 4 is a partial front elevation on the line 4 of Fig. 3.

The embodiment illustrated comprises a frame 10, preferably of wood, and rectangular in shape, over which is tightly stretched 30 a flexible metallic screen or cloth 11 which is held in place by a series of screws or tacks 12. Over this is tightly stretched a sheet of flexible insulating material, as Empire cloth 13, which in turn is held in place by means 35 of a series of screws or tacks 14.

On the front of the Empire cloth 13 is secured a thin sheet metal electrode 15 of tinfoil, sheet aluminum, or the like, by means of a suitable adhesive 15a. The sheet 40 15 has a connector 16, while a connector 17 is connected to the metal cloth or screen 11. By means of these the acoustic condenser may be connected to the output circuit of a radio receiving set or of a phonograph amplifier in a well-known manner.

A fine metal screen, tinsel cloth, or the like may be used as the base for the back electrode 11, and the term "metal fabric" as used in this application is intended to 50 cover structures having these descriptive

properties. Upon the metal fabric 11 is mounted a series of parallel strips of metal 18, shown enlarged in Fig. 3. These strips are preferably of lead foil or tinfoil of from .003" to .007" thickness, and are secured to the metal fabric 11 by soldering, or by a suitable cement, as sodium silicate. A suitable solder for this purpose consists of one part tin, one part lead, and one part bismuth, with a rosin flux.

60 On top of each strip 18 is placed a second and narrower strip 19 of metal which is secured thereto, preferably centrally by means of solder or cement 20.

Both the Empire cloth 13 and the metal 65 fabric 11 are tightly stretched over the frame so that the back of the Empire cloth 13 is normally held closely adjacent to the outermost strips 19, if not actually in contact therewith, particularly as the electrodes 70 11 and 15 are maintained under a normal potential difference which tends to draw them together. For the sake of illustration, however, the Empire cloth 13 is shown in a raised position, which, however, does not 75 exist in actual practice. The thickness of the parts is also greatly exaggerated.

The foregoing acoustic condenser is found to give very excellent results, and particularly will stand heavy pulsating currents 80 without any perceptible amount of flutter, such as was sometimes previously noted, particularly where a heavy current was used due to very great amplification, or the like. It is believed that this result is due very 85 largely to the fact that the narrower strips 19 normally pressed against the back of the empire cloth 13, and as the applied potential varies due to the pulsations therein the attraction of the electrodes 11 and 15 for 90 each other was varied, and this variation causes these electrodes to approach or recede from each other principally between the strips 19.

The result is that a bending action takes 95 place in both the electrodes causing them to bend in a series of waves parallel to and between the strips 19. While this bending is very slight, it takes place over a very large area, and as a result the volume of sound 100

produced is great and is of a very excellent tone quality.

It is found that the strips 18 as arranged in Fig. 3 will work very well when made $\frac{3}{8}$ " in width and spaced $\frac{1}{4}$ ", making the spacing from center to center of the strips 19 about $\frac{5}{8}$ ", while the top strips 19 are $\frac{1}{16}$ " in width.

In Fig. 2 is shown a modification of this idea in which three strips are superimposed one upon the other, and secured to each other and to the metal fabric in substantially the same way.

It will be understood that the metal strips 15 may be rolled or otherwise formed so as to be integral with the center made higher than the edges to give substantially the same result.

While I have described and shown but a few embodiments of my invention, it is to be understood that it is capable of many modifications. Changes, therefore, in the construction and arrangement may be made which do not depart from the spirit and scope of the invention as disclosed in the appended claims.

I claim:

1. In a condenser speaker, a flexible back electrode, a flexible sheet insulator positioned closely adjacent to the front face of the back electrode, a front electrode mounted on the front side of said insulator, said back electrode having a series of spaced raised projections to prevent the insulator from normally contacting with the back electrode over a large portion of the area at one time.

2. In a condenser speaker, a flexible back electrode, a flexible sheet insulator positioned closely adjacent to the front face of the back electrode, a front electrode mounted on the front side of said insulator, said back electrode having a series of spaced raised projections to prevent the insulator from normally contacting with the back electrode over a large portion of the area at one time, said back electrode having air spaces between said projections.

3. In a condenser speaker, a flexible back electrode, a flexible sheet insulator positioned closely adjacent to the front face of the back electrode, a front electrode mounted on the front side of said insulator, said back electrode having a series of spaced raised substantially parallel ridges to prevent the insulator from normally contacting with the back electrode over a large portion of the area at one time, said back electrode having air spaces between said projections.

4. In a condenser speaker, a flexible back electrode, a flexible sheet insulator positioned closely adjacent to the front face of the back electrode, a front electrode mounted on the front side of said insulator, said back electrode having a series of spaced raised substantially parallel ridges of metal

to prevent the insulator from normally contacting with the back electrode over a large portion of the area at one time, said back electrode having air spaces between said projections.

5. In a condenser speaker, a back electrode comprising a metal fabric having a series of spaced parallel metal strips secured thereto, the center of said strips being higher than the side edges, a flexible insulating diaphragm, and a front metal electrode on said diaphragm.

6. In an acoustic reproducer, a sound diaphragm comprising a porous flexible member provided with a plurality of substantially parallel spaced electrode elements, and a co-operating member stretched adjacent thereto.

7. An acoustic condenser consisting of a dielectric diaphragm, an electrode therefor, a co-operating electrode diaphragm therefor, and means to retard the return movement thereof comprising an air compression section therebetween proportioned to retard the return movement the more the greater the force applied thereto.

8. In an acoustic condenser, a metal electrode having a series of raised parallel ridges spaced apart a distance of the order of $\frac{5}{8}$ ", with openings between said ridges to permit of the passage of air, a flexible diaphragm held in front of said electrode and in contact with said ridges whereby a varying voltage applied to said condenser will cause said diaphragm to bend in a series of waves parallel to and between said ridges.

In testimony whereof, I have hereunto set my hand this 15th day of July, 1929.

PHILIP E. EDELMAN.
